UNITED STATES PATENT OFFICE

GEORGE F. STANLEY, OF DAYTON, OHIO, ASSIGNOR TO THE STANLEY MANUFACTURING COMPANY, OF DAYTON, OHIO, A CORPORATION OF OHIO

DESIGN FOR A LABEL

Application filed March 3, 1930. Serial No. 34,719. Term of patent 7 years.

To all whom it may concern:

Be it known that I, GEORGE F. STANLEY, a citizen of the United States, residing at Dayton, in the county of Montgomery and State of Ohio, have invented a new, original, and ornamental Design for a Label, of which the following is a specification, reference being had to the accompanying drawing, forming a part thereof.

In the accompanying drawing:

I claim:

The ornamental design for a label, substantially as shown.

GEORGE F. STANLEY.
